BATHTUB HANGER

William B. Lucke, Wilmette, Ill.

Application May 12, 1932. Serial No. 610,761

10 Claims. (Cl. 4—173)

This invention relates to improvements in hangers for holding and securing a bath tub in position, and one of the objects of the invention is to provide an improved hanger of this character by means of the use of which the weight of the tub will be borne directly by the studding and not by the floor, and which studding also supports the plaster or tiling, thereby obviating the danger of relative displacement of one with respect to the other, caused usually by the settling of the floor with the shrinking of the floor joists, and which settling results in the formation of crevices or cracks between the edge of the tub and the wall of the room.

15 A further object is to provide an improved hanger of this character which is adjustable to compensate tubs of varying sizes and improved means whereby a tight sealing joint will be maintained, thereby preventing water seepage around the edge of the tub.

20 A further object is to provide an improved hanger of this character embodying means for facilitating the placing or setting of the tub in position, and for maintaining the tub against displacement with respect to the hanger.

25 A further object is to provide in a hanger of this character improved means for compensating tubs of different construction.

To the attainment of these ends and the accomplishment of other new and useful objects as will appear, the invention consists in the features of novelty in substantially the construction, the combination and arrangement of the several parts hereinafter more fully described and

30 claimed and shown in the accompanying drawings illustrating this invention, and in which Figure 1 is a view partly in elevation, partly in section and partly broken away of a hanger of this character constructed in accordance with

35 the principles of this invention, and showing a tub in position.

Figure 1a is an enlarged sectional view taken on line 1a—1a, Figure 1.

40 Figure 2 is a top plan view of the hanger in position and a portion of a tub, showing portions of the hanger removed and the manner in which a tub may be readily placed in position.

Figure 3 is an enlarged detail view, partly in elevation and partly in section, showing one end of the tub in position upon the hanger.

45 Figure 4 is an enlarged detail perspective view of one of the sections of the hanger.

Figure 5 is an enlarged detail perspective view

5 of still another section of the hanger.

Figure 7 is a detail perspective view of a portion of one end of one form of a tub.

Figure 8 is a detail sectional view taken on line 60 8—8, Figure 9.

Figure 9 is a sectional view taken on line 9—9, Figure 8.

Figure 10 is a detail sectional view on an enlarged scale on line 10—10, Figure 1.

Figure 11 is an enlarged detail sectional view 65 of a modified form of the invention.

Referring more particularly to the drawings the hanger consists essentially of two body members 15—16 which are preferably constructed in the form of plates of any desired size and thickness, and constructed of any suitable material, each of the plates being provided with apertures 17 therethrough for the purpose of providing a means for forming keys for plaster covering, and some of which apertures may be employed in conjunction with fastening screws 18 which pass therethrough and enter uprights or studs 19, for securing the hanger in position.

70 Each of the members 15 and 16 is provided with a laterally projecting extremity 20 of any desired length and each of the members 15—16 is also provided with a laterally projecting portion 21 at the lower extremity thereof, the forward edge of which is deflected upwardly as at 22 and the 75 extremity of the upwardly deflected portion is again deflected laterally as at 23, the whole forming an upwardly extending hook shaped portion providing a trough 24.

75 End members 25 shaped similarly to the body members 15—16 are also provided with the apertures 17 and the laterally projecting flange portion 23.

The body members 15—16 overlap each other, as shown more clearly in Figures 1, 2 and 10, and the overlapping portions are secured together in any desired or suitable manner such as by means of bolts 26 having nuts 27 threaded thereon, thereby providing a means for adjustably holding the body members 15 and 16 together so that 95 the combined length of the members 15 and 16 may be varied so as to move the end portions 20 of the members 15—16 toward and away from each other to compensate tubs of different lengths.

100 Each of the end members 25 is preferably of sectional construction embodying a main portion and a supplemental section 28 which is also preferably in the form of a plate or the like provided with apertures 29 therethrough. The flange 23 on the main portion of the end members is 105 110

55 of another section of the hanger.

preferably cut away as at 30, and the end section 28 is provided with a laterally deflected portion 31 at the lower edge thereof having an upwardly extending portion 32 spaced from the section 28 and the upper extremity of the portion 32 is deflected laterally as at 33 to form a flange which co-operates with the flange 23. The flange 33 on the end section 28 is so arranged that when the end section 28 is in position with respect to the end member 25, as shown more clearly in Figure 9, the extremity of the flange 33 will terminate short of the flange 23 of the end member 25 to form a space 34 shown more clearly in Figure 9, for a purpose to be set forth.

15 The end sections 28 may be secured in position in any desired or suitable manner, but preferably by means of a fastening bolt 35 which passes through an opening 36 in the end section 28 and also through an opening 37 in the end member 25 for pivotally securing the section 28 to the section 25.

20 The section 28 is also preferably provided with a slot 38 through which a fastening bolt 39 passes, and which bolt also passes through an opening 40 in the end member 25.

25 It will be manifest that with this construction the section 28 will be held against displacement with respect to the end member 25, but by loosening the bolt 39 the end section 28 may be moved about its pivot formed by the bolt 35 passing through the openings 36-37 to permit the section 28 to be adjusted with respect to the end member 25, and after adjustment the bolt 39 may be tightened to secure the section 28 in its adjusted position.

30 If desired the end sections 28 may be entirely detached from the members 25, as shown in Figure 2, to permit insertion of the tub.

35 In use, the members 15 and 16 may be secured together by the bolts 26 so as to provide the proper combined length of the members before they are secured in position with respect to the upright, if the construction of the upright will not permit of the adjustment during the assembling 40 of the parts. When, however, access may be had to the members 15-16 between the uprights before plastering or wall construction is provided, one of the members 15-16 may be secured in position and to the uprights 19 and then the other member secured in position so as to overlap the first member, the fastening bolts 26 being then inserted.

45 The end members 25 may be similarly secured in position and, as before stated, the end sections 28 may be disconnected from the end members 25, or the fastening bolts 39 loosened to permit the end members to be moved about their pivots and the fastening bolts 39 removed so as to permit the end sections 28 to be swung about their 50 pivots out of the way.

55 The tub 40 may be then placed in position as shown in Figure 2 by sliding the same into the frame formed by the body and end members of the hanger and in a manner that the flanges 23 of the hanger members will engage under the rim of the tub, as shown more clearly in Figures 8, 9, and 10. This will cause the flanges 23 to contact with the lower surface of the rim or adjacent portion of the tub. The end sections 28, if detached may then be applied or secured 60 in position to the members 25.

65 In the form of tubs 40 which are provided with a brace or arm at the ends thereof, such brace or arm will assume a position within the recess formed by the proximate ends of the flanges 70

75-33 on the end members 25 and end sections 28.

80 If desired when the tub is placed in position sealing material 42 of any suitable composition may be placed between the portions 22, 23 and 24 of the body members and the corresponding parts of the end members and the adjacent faces of the tub to form fluid tight joints.

85 In the form of tubs which are provided with a depending portion 43 on the rim, such portion will enter the troughs 24 formed on the hanger, and in other forms of tubs as shown at 44 in Figure 11, which are not provided with a depending portion 43, the rim of the tub will rest upon the flange 22 and the sealing material 42 may be placed within the trough and between the 90 edge of the tub and the hanger.

95 The supporting portions of the hanger are so constructed that no matter what form of tub is employed sufficient space is provided to permit of an adjustment of the tub with respect to the hanger to properly position the tub.

100 In some form of tubs, as shown more clearly in Figure 7, the rim 45 is provided with an inclined lower surface 46, whereas in other forms of the tub, this portion 46 will be straight. In 105 order to compensate these varying constructions, the end sections 28 of the hangers are connected to the end members 25 for adjustment with respect thereto, preferably about the pivot 35 (see Figure 9), thereby permitting the end section to 110 be adjusted so that the flange 33 thereon will be properly positioned to engage the lower edge 46 of the tub.

115 Some tubs are provided with what is termed a depending apron 47 which extends downwardly and terminates in close proximity to the floor of the room. In order to provide a fluid tight joint between the lower extremity of the apron and the floor of the room, a floor joint is employed which is preferably formed of plates 48-49 having apertures 50 therethrough and an upwardly projecting flange 51 along the rear edge thereof. These plates are overlapped at their inner ends and are secured together by fastening bolts 52, permitting the plates to be adjusted longitudinally one 120 with respect to the other to compensate tubs of varying lengths.

125 The plates are secured to the floor 53 in any suitable manner and after the tub is placed in position (see Figure 1a) the lower edge of the apron 47 will be disposed within the angle formed by the members 49 and upright portions 51 and sealing material 54 may be employed to cover the plates 48 and in which sealing material the lower edge of the apron is embedded, the apron 130 being preferably spaced from the upright 51 so as to permit a portion of the sealing material to pass behind the apron, thereby forming a liquid tight joint.

135 With this improved construction it will be manifest that the tub will not only be suspended by the uprights of the building but the entire weight of the tub will be sustained by the hanger and the tub will be prevented from tilting in the event that pressure is exerted to any particular 140 portion thereof around the edge or rim of the tub.

145 Furthermore, the hanger is constructed in such a manner that it is adjustable to compensate tubs of varying sizes, thereby obviating the necessity of manufacturing the parts of the hanger in different sizes to accommodate different size tubs.

150 While the preferred forms of the invention have been herein shown and described, it is to be understood that various changes may be made

- in the details of construction and in the combination and arrangement of the several parts, within the scope of the claims, without departing from the spirit of this invention.
5. What is claimed as new is:—
1. Means for supporting a bath tub, embodying a hanger comprising a body portion formed of overlapping members secured together for adjustment whereby the length of the hanger may be varied, end members secured to the respective body members at substantially right angles thereto, said end members embodying sections secured together and adapted for relative adjustment, said body members and end members provided with laterally projecting flanges adapted to engage under the rim of a tub for supporting the tub, and means for securing the said hanger to an upright, one of the sections of each end member adapted to be shifted with respect to its co-operating section, and out of the way of a portion of a tub, to permit the tub to be readily positioned with respect to the hanger and then moved back into operative position with relation to the tub.
  2. Means for supporting a bath tub, embodying a hanger comprising a body portion formed of overlapping members secured together for adjustment whereby the length of the hanger may be varied, end members secured to the respective body members at substantially right angles thereto, said body members and end members provided with laterally projecting flanges adapted to engage under the rim of a tub for supporting the tub, means for securing the said hanger to an upright, the said end members being of sectional construction secured together and adapted for relative adjustment with respect to each other and the body members, one of the sections of each end member adapted to be shifted with respect to its co-operating section and out of the way of a portion of a tub, to permit the tub to be readily positioned with respect to the hanger and then moved back into operative position with relation to the tub, and means for securing the shiftable sections of said members against such movement.
  3. Means for supporting a bath tub, embodying a hanger comprising a body portion formed of overlapping members secured together for adjustment whereby the length of the hanger may be varied, end members secured to the respective body members at substantially right angles thereto, said body members and end members provided with laterally projecting flanges adapted to engage under the rim of a tub for supporting the tub, and means for securing the said hanger to an upright, the said end members being of sectional construction secured together and adapted for relative adjustment with respect to each other and the body members, one of said sections of each end member adapted to be shifted with respect to its co-operating section and out of the way of a portion of a tub, to permit the tub to be readily positioned with respect to the hanger and then moved back into operative position with relation to the tub, portions of the said flanges of the end members being cut away.
  4. Means for supporting a bath tub, embodying a hanger comprising a body portion formed of overlapping members secured together for adjustment whereby the length of the hanger may be varied, end members secured to the respective body members at substantially right angles thereto, said body members and end members provided with laterally projecting flanges adapted
- to engage under the rim of a tub for supporting the tub, the said end members embodying a section pivotally connected thereto adapted to be adjusted to different angles with respect to the remaining portion of the respective end members, and means for securing said sections in such adjusted positions.
5. Means for supporting a bath tub, embodying a hanger comprising a body portion formed of overlapping members secured together for adjustment whereby the length of the hanger may be varied, end members secured to the respective body members at substantially right angles thereto, said body members and end members provided with laterally projecting flanges adapted to engage under the rim of a tub for supporting the tub, the said end members embodying a section pivotally connected thereto adapted to be swung out of the way of a portion of the tub to facilitate positioning the tub with respect to the hanger and then moved back into operative position with respect to the tub, said sections also adapted to be adjusted to vary the angle of the supporting flange thereon with respect to the end member, and means for securing said sections in their adjusted positions.
6. Means for supporting a bath tub, embodying a hanger comprising a body portion formed of overlapping plate sections adjustably secured together and adapted to be secured to an upright, laterally projecting end members comprising sections adjustably secured together to compensate tubs of varying lengths and widths, a laterally projecting flange arranged along all of said members and adapted to engage under the rim of the tub, said flanges extending for a substantial distance from the face of the respective members to permit of lateral and endwise adjustment of the tub to position the same before the latter is secured in position, and sealing means between the tub and an adjacent portion of the hanger.
7. Means for supporting a bath tub, embodying a hanger comprising a body portion formed of overlapping plate sections adjustably secured together and adapted to be secured to an upright, laterally projecting end members comprising sections adjustably secured together whereby said supporting means will compensate tubs of varying lengths and widths, and a laterally projecting flange arranged along all of said members and adapted to engage under the rim of the tub, said flanges extending for a substantial distance from the face of the respective members to permit of lateral and endwise adjustment of the tub to position the same before the latter is secured in position.
8. Means for supporting a bath tub, embodying a hanger comprising a body portion formed of overlapping members secured together for adjustment whereby the length of the hanger may be varied, end members secured to the respective body members at substantially right angles thereto, said body members and end members provided with laterally projecting flanges adapted to engage under the rim of a tub for supporting the tub, the said end members embodying a section connected thereto and carrying a laterally projecting flange, said section adapted to be adjusted with respect to the remaining portion of the respective end members to position the flange carried thereby at a different angle with respect to the flange on another section of the end member, and means for

securing said sections in such adjusted positions.	80
9. Means for supporting a bath tub, embodying a hanger comprising a body portion formed of overlapping members secured together for adjustment whereby the length of the hanger may be varied, end members secured to the respective body members at substantially right angles thereto, said body members and end members provided with laterally projecting flanges adapted to engage under the rim of a tub for supporting the tub, the said end members embodying a section connected thereto and carrying a laterally projecting flange, said section adapted to be adjusted with respect to the remaining portion of the respective end members to position the flange carried thereby at a different angle with respect to the flange on another section of the end member, and means for securing said sections in such adjusted positions, portions of the flanges on the end members being cut away to receive the flanges on the adjustable sections of the respective end members.	85
10. Means for supporting a bath tub, embodying a hanger comprising a body plate, end members secured to the plate at substantially right angles thereto, said plate and end members provided with laterally projecting flanges adapted to engage under the rim of a tub for supporting the tub, the end members embodying a section connected thereto and carrying a laterally projecting flange, said section adapted to be adjusted with respect to the remaining portion of the respective end members to position the flange carried thereby in a different plane with respect to the flange on another section of the end member, and means for securing said section in such adjusted position.	90
